PHOTOGRAPHIC FILM VIEWER

Richard P. Fuller, North Hollywood, Calif., assignor to
Craftsmen's Guild, Hollywood, Calif., a partnership

Application June 1, 1954, Serial No. 30,756

Term of patent 14 years

(Cl. D61—1)

To all whom it may concern:

Be it known that I, Richard P. Fuller, a citizen of the United States and a resident of North Hollywood, California, have invented a new, original, and ornamental Design for a Photographic Film Viewer, of which the following is a specification, reference being had to the accompanying drawing, forming part thereof.

Referring to the drawing:

Fig. 1 is a perspective view of a photographic film viewer, showing my new design;

Fig. 2 is a top plan view thereof;

Fig. 3 is a side elevational view thereof;

Fig. 4 is a bottom plan view thereof;

Fig. 5 is a front elevational view thereof; and
Fig. 6 is a rear elevational view thereof.

I claim:

The ornamental design for a photographic film viewer, as shown.
